UNITED STATES PATENT OFFICE.

WALTER EVERETT MOLINS, OF LONDON, ENGLAND.

APPARATUS FOR FEEDING AND ARRANGING OVAL CIGARETTES.

Application filed October 6, 1924. Serial No. 742,047.

To all whom it may concern:

Be it known that I, WALTER EVERETT MOLINS, a citizen of the United States of America, residing in London, England, have invented a certain new and useful Apparatus for Feeding and Arranging Oval Cigarettes, of which the following is a specification.

This invention relates to apparatus for feeding oval cigarettes from a hopper and for subsequently lapping them over one another in the usual style of packed oval cigarettes.

The apparatus is preferably combined with means for arranging the lapped cigarettes in groups of the required number, but it is to be understood that the methods employed forlapping the cigarettes may be utilized in connection with feeding apparatus without the grouping means if desired.

The feeding apparatus employed is preferably of the known fluted drum type, such as is described for example in the specification of United States Patent No. 1506498.

According to the invention as each cigarette leaves the drum flutes it is positively turned or sloped automatically at the correct angle to cause it to fall on the preceding cigarette in the correct lapped manner and means are also provided for causing the cigarettes to be retained in the lapped condition during the further travel through the apparatus.

Various methods may be employed for turning the cigarettes, for example, the rear edge of a drum flute may be caused to press on the rear edge of a cigarette to turn it, in combination with a spring pressed pawl or the like which regulates the position of the turned cigarette, or wheels arranged with their peripheries travelling at a faster rate than the drum flutes may be arranged to engage the ends of each cigarette to turn it, or rotating discs having projections thereon may be arranged to engage the cigarettes as they pass from the drum flutes to turn them in combination with an automatic stop.

The cigarettes after being turned into the lapped position may be held therein by being caused to travel between a guide plate and a brush or between pairs of brushes, or between guide plates co-operating with a movable stop member, or by other suitable friction means.

To enable the invention to be fully understood it will now be described by reference

to the accompanying drawings in which the invention is shewn applied to an apparatus of the general construction described in United States specification No. 1506498 60 aforesaid.

In the drawings:—

Fig. 1 is a side elevation of a portion of the hopper feed end of the apparatus shewing one arrangement for turning oval ciga- 65 rettes according to the invention, and

Fig. 2 is an end elevation thereof.

Fig. 3 is a side elevation of the bridge end of the apparatus over the transfer conveyor, shewing one method of controlling 70 the cigarettes, and

Fig. 4 is a front elevation thereof.

Fig. 5 is a view similar to Fig. 3 but shewing a different method of control, and

Fig. 6 is a front elevation thereof. 75

Fig. 7 is a side elevation of one end of the apparatus adjacent to the feed and shewing a further arrangement for turning the cigarettes, and

Fig. 8 is an end elevation thereof. 80

Fig. 9 is a view of a detail.

Fig. 10 is a view of Fig. 9 looking in the direction of the arrow K.

Figure 11 is a detail of Figure 1 showing an arrangement of slanting brushes; and 85

Figure 12 is a detail of a portion of Figure 5 also showing an arrangement of slanting brushes.

Referring first to Figs. 1 and 2, the fluted drum 1, roller 2, hopper 3 and forked 90 plate 4 are similar to and operate as already described in specification No. 1506498, the overhead grouping device being indicated at 10.

The cigarettes are removed from the drum 1 by the forked plate 4 and as they begin to leave the flutes they pass beneath a pawl 5 which is pressed downwards by a light spring 6. The pawl 5 is preferably made in two parts as shewn in Figs. 9, 10 comprising outer fingers 7, and a slightly longer central finger 8.

As will be seen in Fig. 1, the outer fingers 7 press on the cigarette behind the cigarette on which the finger 8 presses. While 105 the cigarette is under the fingers the drum is still carrying it forward, the friction on the leading edge of the cigarette causing it to lag and as the rear of the cigarette is urged forward by the drum, a turning effect 110 is produced which tilts the cigarette to the required angle.

The outer fingers 7 perform the main turning operation while the central finger 8 gives the cigarette a final stroking motion and as the cigarette leaves the drum it will 5 be seen that the tips of the drum flutes bear on the rear of the cigarette and give it a final twist in the correct direction.

As the tilted cigarette leaves the fingers 7 it passes between an upper control plate 10 10 9 and a narrow brush 10^a which is arranged along the centre of the plate 4 and extends from the point where the cigarette is received to the bridge end of the apparatus over the transfer conveyor. The bristles of 15 the brush extend upwards for about half the distance between the plates 4 and 9.

Once the cigarettes have been engaged between the brush and the plate they cannot change their tilted position. The conveyor 20 11 and its pusher piece 10 operate to group the cigarettes in the manner described in specification No. 1506498.

An additional means for turning the cigarettes may also be provided comprising a 25 pair of friction discs 12 rotating in the direction of the arrow A on pins 13 carried in frames 14 pivoted on the spindle of the fluted roller 2. These discs are preferably of metal and knurled or they may be faced 30 with rubber or other friction material and each is provided with a grooved extension 15 on which a rubber ring 16 is stretched. A spring 17 causes the ring 16 to make contact with the inside of the rim of the fluted 35 drum 1 causing the discs 12 to be driven as the drum rotates. This drive is so proportioned that the rim speed of the discs is greater than that of the drum, and the discs are arranged to lift the cigarettes slightly 40 from the bottoms of the flutes, the greater speed of the discs causing the cigarettes to rotate slightly in the direction required, relieving the work to be done by the pawl 5 and drum flutes to a considerable extent.

45 Figs. 3 and 4 shew one method of controlling the cigarettes at the point of delivery to the bridge 18 over the transfer conveyor (not shewn).

In this case the cigarettes are shewn as 50 delivered from the drum 1, tilted or lapped and passing between the plate 4 and an upper guide plate 9 which is extended over the bridge 18.

The plate 4 is fitted with the bottom brush 55 10^a shewn in Fig. 1 as will be readily understood. A swinging stop plate 19 pivoted on a bracket 20 meets each group of cigarettes just before they reach the bridge 18.

60 The plate 19 is operated by a cam 21 mounted on the spindle of one of the sprocket wheels of the upper conveyor 11 through the medium of a roller 22, cam rod 23 and a link 24, and moves outward at the same speed as that of the cigarettes moving

on to the bridge. After the passage of the transfer conveyor pusher piece through the slot 18^a in the bridge, which clears the cigarettes off the bridge, the plate 19 returns rapidly under the action of a spring 25 to 70 meet the next group of cigarettes.

In the arrangement shewn in Figs. 5 and 6 the cigarettes are controlled at the bridge end by a pair of small brushes 26 mounted above the bridge with bristles projecting 75 downwards. The cigarettes thus pass from the control of the long bottom brush on plate 4 into the control of the upper brushes and cannot become displaced. If desired, the brush surface of the bristles of all or any of the brushes 10^a, 26, may be slanting so that they are shorter at the point of entry of the cigarettes and longer at the exit end. 80

The number and position of the brushes may also be varied as desired. 85

In Figs. 7 and 8 an arrangement is shewn for lapping the cigarettes in a reverse direction after they have left the fluted drum 1. In this arrangement, the feed drum 1 delivers the cigarettes on to the forked plate 4 as in the aforesaid specification and no turning apparatus is provided. 90

A pair of rotating plates 27 having a number of projections 28 on their peripheries are secured to the spindle 29 of the sprocket 95 wheel 30 of the upper conveyor.

The projections 28 are so shaped that when one comes behind a cigarette the latter is tilted until it lies at the required angle. A moving stop 30^a is arranged to project up 100 from the surface of the plate 4 in front of the first of a group of cigarettes. This stop is pivoted at 31 and operated by cam 32 on the spindle 29 through roller 33 and cam lever 34, a spring 35 causing it to rise as the roller 33 drops into the recess of the cam. When the second cigarette of the group touches the first one, the roller 33 runs up the rise of the cam 32 and the stop 30^a drops flush with the plate 4, and remains down 110 until the next group comes along. The first cigarette is then lying on a cork or like inset 36 fitted in the plate 4 and the friction of this inset is sufficient to prevent the cigarettes from slipping into the horizontal position. Another moving stop 37 operates 115 from above the cigarettes and drops behind each cigarette as it joins its group. It does not, however, drop behind the last cigarette of a group as the conveyor piece 10 is timed to reach the group as the last one is gathered. This stop 37 is secured to a lever 38 pivoted at 39, the upper end of the lever carrying a roller 40 running on a cam 41 mounted on the spindle 29. A spring 42 pulls the lever 38 down at the moment when the roller is free to run down the cam 41. 120

The apparatus illustrated in Figs. 7 and 8 is adapted to deal with groups of five cigarettes and thus the cam 41 has four de- 125

pressions and a dwell for the fifth cigarette; the rotary plates 27 have five projections, while the cam 32 for the bottom stop 30^a has only one depression as its operates only 5 once per group.

Obviously the apparatus may be modified to deal with groups of any desired numbers.

The invention can also be adapted to operate with a fluted belt or conveyor working 10 in the hopper in place of the fluted drum 1, or with other known types of feed.

It will be understood that the drum flutes may be shaped to any particular shape which is found to be most advantageous 15 for dealing with oval cigarettes according to the invention.

Having thus described the nature of my said invention and the best means I know 20 of carrying the same into practical effect, I claim:—

1. Apparatus for arranging oval cigarettes in lapped formation in the usual style of packed oval cigarettes comprising a hopper, means for delivering the cigarettes from the 25 hopper, means for positively turning automatically each cigarette upon leaving the delivery means, into a slanting or sloped position and means for retaining the cigarettes in such position while they are continuously moved for grouping, transferring 30 or other similar operations.

2. Apparatus for arranging oval cigarettes in lapped formation in the usual style of packed oval cigarettes, comprising a hopper, a fluted conveyor for delivering the 35 cigarettes from the hopper, a resilient finger adjacent said conveyor beneath which the cigarettes are moved, said resilient finger and the rear edge of a flute of said conveyor 40 serving to positively turn each cigarette into a sloping position.

3. Apparatus for arranging oval cigarettes in lapped formation in the usual style of packed oval cigarettes, comprising a hopper, a fluted conveyor for delivering the cigarettes from the hopper, a resilient finger adjacent said conveyor beneath which the cigarettes are moved, said resilient finger comprising a short prong adapted to cooperate 45 with the rear edge of each flute of said conveyor to arrange the cigarette carried thereby in a sloping position, and a longer prong adapted to engage the positioned cigarette beyond that engaged by the short prong.

4. Apparatus for arranging oval cigarettes in lapped formation in the usual style of packed oval cigarette, comprising a hopper, a fluted conveyor for delivering the cigarettes from the hopper, a resilient finger adjacent said conveyor beneath which the cigarettes are moved, said resilient finger and the rear edge of a flute of said conveyor serving 50 to positively turn each cigarette into a sloping position, and means for retaining the

cigarettes in such position while they are continuously moved for grouping.

5. Apparatus for arranging oval cigarettes in lapped formation in the usual style of packed oval cigarettes, comprising 70 a hopper, a fluted conveyor for delivering the cigarettes from the hopper, a resilient finger adjacent said conveyor beneath which the cigarettes are moved, said resilient finger comprising a short prong adapted to 75 cooperate with the rear edge of each flute of said conveyor to arrange the cigarette carried thereby in a sloping position, and a longer prong adapted to engage the positioned cigarette beyond that engaged by the short prong, and means for retaining the cigarettes in such position while they are continuously moved for grouping.

6. Apparatus for arranging oval cigarettes in lapped formation in the usual style of packed oval cigarettes comprising 85 a hopper adapted to contain cigarettes, a fluted conveyor for delivering the cigarettes from the hopper, a resilient finger adjacent said hopper adapted to engage said cigarettes in said flutes, means adjacent said conveyor having a surface rotating at a greater peripheral speed than said flutes, each cigarette in turn being engaged on opposite sides by said finger and surface respectively 90 and tilted to the desired angle, and means to retain said tilted cigarettes in their desired position while moving them from said conveyor.

7. Apparatus for arranging oval cigarettes in lapped formation in the usual style of packed oval cigarettes comprising a hopper adapted to contain cigarettes, a fluted conveyor having peripheral grooves for 100 delivering cigarettes from said hopper one in each flute, a forked plate having the ends of the forks in said peripheral grooves to remove cigarettes from said conveyor, means to turn all said cigarettes into a desired slanting position before delivery on said plate, an endless conveyor above said plate 105 and means thereon to group said cigarettes and move them along said plate.

8. Apparatus for arranging oval cigarettes in lapped formation in the usual style of packed oval cigarettes comprising a hopper adapted to contain cigarettes, a fluted conveyor having peripheral grooves 110 for delivering cigarettes from said hopper one in each flute, a forked plate having the ends of the forks in said peripheral grooves to remove cigarettes from said conveyor, means to turn all said cigarettes into a desired slanting position before delivery on said plate, means thereon to group said cigarettes and move them along said plate, a guide plate arranged above said forked plate, a brush carried by said forked plate, the cigarettes being delivered between the bristles of the brush and the guide plate 115 120 125 130

and then retained in their slanting position during their travel.

9. In a cigarette packing machine for oval cigarettes, a hopper, a carrier plate, means to deliver said cigarettes from said hopper to said plate in overlapping, sloped relation, a guide plate over said carrier plate, a conveyor to move said cigarettes between said plates, a slotted bridge at the ends of said plates, a transfer conveyor having pusher pieces passing through said slot, a brush over said bridge having depending bristles, said cigarettes being delivered onto said bridge from said plates and retained in their sloped relation by the bristles of said brush.

10. Apparatus for arranging oval cigarettes in lapped formation in the usual style of packed oval cigarettes comprising a hopper adapted to contain cigarettes, a carrier plate, means to deliver said cigarettes one at a time onto said carrier plate in an overlapped slanting position, a conveyor adapted to move said cigarettes along said carrier plate, and friction means to retain said cigarettes in their delivered position throughout their movement along said carrier plate.

11. Apparatus for arranging oval cigarettes in lapped formation in the usual style of packed oval cigarettes comprising a hopper adapted to contain cigarettes, a carrier plate, means to deliver said cigarettes one at a time onto said carrier plate in an overlapped slanting position, a conveyor adapted to move said cigarettes along said carrier plate, and friction means including bristles on said carrier plate to retain said cigarettes in their delivered position throughout their movement along said carrier plate.

12. Apparatus for arranging oval cigarettes in lapped formation in the usual style of packed oval cigarettes comprising a hopper adapted to contain cigarettes, a carrier

plate, means to deliver said cigarettes one at a time onto said carrier plate in an overlapped slanting position, a conveyor adapted to move said cigarettes along said carrier plate, and friction means including bristles on said carrier plate to retain said cigarettes in their delivered position throughout their movement along said carrier plate, said bristles having their ends lying in a plane inclined to said plate and closer thereto at the delivery end than at the exit end.

13. Apparatus for arranging oval cigarettes in lapped formation in the usual style of packed oval cigarettes comprising a hopper adapted to contain cigarettes, a carrier plate, means to deliver said cigarettes one at a time onto said carrier plate in an overlapped slanting position, a conveyor adapted to move said cigarettes along said carrier plate, and friction means including bristles on said carrier plate to retain said cigarettes in their delivered position throughout their movement along said carrier plate, said bristles having their ends lying in a plane inclined to said plate and closer thereto at the delivery end than at the exit end, and a guide plate parallel to said carrier plate and spaced above said bristles.

14. Apparatus for arranging oval cigarettes in lapped formation in the usual style of packed oval cigarettes, comprising a hopper, a fluted conveyor for delivering cigarettes from said hopper, a resilient finger adjacent said conveyor beneath which the cigarettes are moved, said resilient finger comprising three independently pivoted prongs, the central prong being the longest and adapted to engage a cigarette beyond that engaged by the outer two prongs for the purpose described.

In testimony whereof I have signed my name to this specification.

WALTER EVERETT MOLINS.
